(57) **CLAIM**

The ornamental design for a forage cap, as shown and described.

DESCRIPTION

FIG. 1 is a front-right perspective view of a design for a forage cap according to the present invention;

FIG. 2 is a top plan view thereof;

FIG. 3 is a front elevation view thereof;

FIG. 4 is a rear elevation view thereof;

FIG. 5 is a rear-right perspective view thereof;

FIG. 6 is right side elevation view thereof;

FIG. 7 is a left side elevation view thereof;

FIG. 8 is a bottom plan view thereof;

FIG. 9 is a front-right perspective view thereof, showing example optics positioned on the forage cap; and,

FIG. 10 is a rear elevation view thereof, showing example optics positioned on the forage cap.

The broken lines shown as part of the cap itself illustrate features of the article of manufacture that form no part of the claimed design. The broken lines illustrating optics represent environmental structure that forms no part of the claimed design.
